W. E. RICHARD

HEADLIGHT

Filed May 10, 1923

UNITED STATES PATENT OFFICE.

WILLIAM E. RICHARD, OF EVANSVILLE, INDIANA.

HEADLIGHT.

Application filed May 10, 1923. Serial No. 637,973.

My invention relates to improvements in reflectors and it is one of the objects of my invention to provide a reflector particularly adaptable for headlight purposes for automobiles and the like which will project the rays of light from the lamp in such a manner as to cause the greater proportion of the light to be projected below a plane which will cause a dangerous glare of light in the eyes of drivers of approaching vehicles. Other objects and advantages of my invention will appear more fully in the accompanying specification and claim.

For the purpose of disclosing my invention I have illustrated one embodiment thereof in the accompanying drawing in which the figure is a longitudinal section of a headlight embodying my invention.

In the structure illustrated the reflector 1 is in the form of a truncated ellipsoid with the lamp 2 arranged at the apex of the ellipsoid and a cover plate preferably in the form of a front glass 3 arranged at the base or truncated portion of the ellipsoid. This reflector may be arranged in any suitable enclosing casing 4 which at one end is provided with a lamp receiving socket 5 adapted to project through the reflector. The reflector is provided with an annular lip 6 between which and a ring 7 secured on the casing may be arranged the cover plate. The filament of the lamp is adjusted to the focus 8 of the reflector and the cover plate 3 is arranged in the plane of the focus 9 of

the reflector. As has heretofore been stated, 35 this cover plate may take the form of a glass and at the focal point of the reflector the glass is preferably left clear or provided with a lens, while the remaining portion of the glass may be either opaque or semi-transparent to thus cut off or diffuse the small cone of direct rays emanating from the focus of the lamp.

If desired, a deflector 10 may be placed inside the reflector and below the focus so 45 as to deflect all of the lower reflected rays outwardly and downwardly through the focal opening. While I have illustrated and described this deflector as being within the reflector and below the focal point 50 thereof, it may be, if desired, be exterior to the casing and above the focal point and accomplish the same result.

I claim as my invention:

A reflector substantially ellipsoid in shape 55 and truncated at its second focal point, a translucent cover plate fitting said truncated portion and having at the second focal point of the reflector a transparent portion and a deflector arranged at said transparent portion and constructed to deflect all of the lower reflected rays outwardly and downwardly.

In witness whereof I, WILLIAM E. RICHARD, have hereunto set my hand at 65 Evansville, Indiana.

WILLIAM E. RICHARD.
